H. H. Styll & K. Parsons

ATTORNEYS

UNITED STATES PATENT OFFICE.

HARRY W. HILL, OF SOUTHBIDGE, MASSACHUSETTS, ASSIGNOR TO AMERICAN OPTICAL COMPANY, OF SOUTHBIDGE, MASSACHUSETTS, A CORPORATION OF MASSACHUSETTS.

LENS-GRINDING APPARATUS.

Application filed April 2, 1920. Serial No. 370,724.

To all whom it may concern:

Be it known that I, HARRY W. HILL, a citizen of the United States, residing at Southbridge, in the county of Worcester 5 and State of Massachusetts, have invented certain new and useful Improvements in Lens-Grinding Apparatus, of which the following is a specification.

This invention relates to improvements in 10 lens grinding apparatus and has for its principal object the provision of a novel and improved construction of automatic mechanism for grinding or polishing lenses and for keeping the lens surface suitably supplied with the abrasive fluid during the 15 grinding operation.

A further object of the present invention is the provision of mechanism for this purpose which shall be simple of construction, 20 shall be lighter than mechanism hitherto employed for similar purposes, and more efficient in its operation.

Other objects and advantages of my improved construction should be readily apparent by reference to the following specification taken in connection with the accompanying drawings, and it will be understood that any modifications in the specific details 25 of construction shown and described may be made within the scope of the appended 30 claim without departing from or exceeding the spirit of the invention.

Figure I is a vertical sectional view of a 35 machine embodying the invention.

Figure II is a sectional view of the bowl and the lap mounted on the lower spindle 1.

Prior to the present invention certain attempts have been made in the production of lenses to render the operation substantially 40 automatic, in that a bowl has sometimes been fastened to a rotating lower lens grinding shell and a scraper or the like employed, serving to throw the material forced outwardly by centrifugal action in toward the center where the grinding tool is located. 45 Mechanism of this type, however, has been found to be open to certain objections due to the fact that at the outset it is necessary to supply a considerable quantity of abrasive in suspension within the bowl before the quantity is sufficient to be operated upon by the centrifugal action of the whirler and by the scraper to throw the material inward, making considerable weight on the spindle

and requiring a heavily constructed machine. 55 Secondly, this mechanism is particularly open to objection in the commercial production of lenses due to the fact that when the grinding action ceases if the bowl is not immediately cleaned the abrasive material will settle to the bottom and harden 60 so that if left without attention during the lunch hour for example, when the workman comes back considerable time must be expended in loosening and softening up the 65 hardened material and the cost of production as well as the time required is thus considerably increased.

It is to obviate these difficulties and provide a simple, light and inexpensive mechanism which may be readily cared for, which 70 will commend itself either for factory usage, where a large number of lenses are to be ground on the same tool, or for prescription work, where a single lens is to be finished on 75 the tool with different grades of abrasive, that the present construction has been devised.

In the drawing, Figure I, there is disclosed the mechanism as comprising a lower 80 spindle 1 driven through the medium of the pulley 2, and having mounted thereon the improved grinding tool. This grinding tool comprises the bowl 24, having a rim 25. The bowl is conical, and its threaded portion 85 23 is mounted on the threaded part of the spindle, and secured thereon by the lock nut 28 and the washer 29, which, as at 30, is keyed on the spindle to prevent any disarrangement of the adjusting mechanism, 90 through contact of the parts with the table 19 and the spindle bearing. The lock nut 28 serves to lock the bowl in vertical adjusted positions.

The inner periphery of the rim of the 95 bowl is provided with a web 26, which fits tightly against the end 27 of the head portion, preferably constituting the laps 4 for grinding lenses 5 on the lens block 6. These lens blocks 6 are shown as rotatably mounted on 100 the cone points 7 of the spider 8, which is in turn rotatably mounted on the pin 9 of the pitman arm or link 10. This arm is secured to the adjustable eccentric pin 11 on the driven disc 12, which as it is rotated serves 105 to impart a reciprocating movement to the arm 10 and thus shifts the lens holders and lenses transversely of the lap 4. The web

26, adjacent where it is integral with the rim 25, has a groove or trough 14 at the edge of the lap 4 providing a space so that the lenses in their reciprocations if of sufficient 5 size, may move over to somewhat overhang the edge of the lap 4 and also providing a space which serves as a trough and receptacle for the abrasive bearing fluid. A substantially triangular scraper member 16 is 10 carried by the arm 17 hinged to the bracket 18 which rises from the table 19, the scraper extending down to the bottom of the trough and thus scraping loose the abrasive material lying at the bottom and throwing it inward toward the center of the lap 4 to keep a constant supply of abrasive fluid on the surface of the lap 4.

From the foregoing description it will be noted that there has been devised an improved mechanism comprising a central lens holding or grinding member illustrated as of convex form, having immediately adjacent the edge thereof a relatively slight abrasive receiving groove or channel and 25 upstanding retaining rim, the abrasive receiving space being of size to require but a small amount of abrasive to operate satisfactorily, thus lessening the weight of the

parts, the amount of abrasive required, and rendering it extremely simple to clean out 30 all old abrasive when a finer type is to be used, or making it easy to break up the dried out abrasive should the machine be brought to rest for a more or less continued period.

35

I claim:

A lens grinding tool including a threaded spindle, a lap portion mounted upon the upper end thereof, an abrasive receiving bowl having a central threaded opening within 40 its bottom for adjustably mounting said bowl, a web portion formed integral with said bowl upon the interior thereof and adapted to fit tightly against the faces of the lap portion, said web portion being 45 curved upwardly at its inner edge to form an abrasive receiving groove and means for retaining said bowl in an adjusted position upon the spindle.

In testimony whereof I have affixed my 50 signature, in presence of two witnesses.

HARRY W. HILL.
